ELECTRIC CLOCK MOUNTING

William Meyncke, Lynwood, Calif., assignor to
 Grayson Heat Control, Ltd., Lynwood, Calif.,
 a corporation of California

Application August 17, 1938, Serial No. 225,259

2 Claims. (Cl. 161—1)

This invention relates to means for mounting electric clocks upon cooking stoves, ranges, or the like and aims to provide a mounting from which the clock may be readily detached and removed when desired without disturbing the wiring. Heretofore electric clocks on stoves and the like have received their source of current through wires extending outside of the range or stove, usually at the back thereof. In order to obviate strains on the internal connection of the clock which might cause short circuits or fires, the underwriters' requirements provide for the employment of some sort of strain relief to prevent the transmission to these connections of any strains exerted upon the cord.

One of the purposes of my present invention is to eliminate the necessity for the use of such strain relief devices and to electrically connect the clock with the source of current without the employment of exposed wires or cords, such as might be subjected to strains.

Another purpose of the invention is to provide a clock mounting which will enable the clock to be detached for servicing when required without disconnecting any wires and which will automatically reestablish the circuit when the clock is replaced in position.

Other objects and inherent advantages of my invention will be readily appreciated as the same becomes better understood by reference to the following description when considered in connection with the accompanying drawings.

Referring to the drawings:

Fig. 1 is a fragmentary side elevation of a stove or range equipped with my invention;

Fig. 2 is a fragmentary front elevation showing the clock in position;

Fig. 3 is a rear elevation of the clock case and mounting panel;

Fig. 4 is a fragmentary sectional view on the line 4—4 of Fig. 3;

Fig. 5 is a bottom view of the mounting panel;

Fig. 6 is a perspective view of said panel;

Fig. 7 is a fragmentary front elevation of a range equipped with a modified form of mounting;

Fig. 8 is a rear elevation of the clock case and mounting panel shown in Fig. 7;

Fig. 9 is a perspective view of the front face of the mounting panel;

Fig. 10 is a bottom view of the panel;

Fig. 11 is a fragmentary sectional view on the line 11—11 of Fig. 8.

Referring to the drawings more in detail, and particularly to Figs. 1 to 6 thereof, reference char-

acter 12 indicates generally a stove or range of any preferred construction illustrated as of the electric type. The range in this instance is equipped at the rear with a mounting panel generally indicated by 13 which is supported upon a bracket 14 within which the wiring connecting the stove bus bars with the panel are concealed.

The panel itself consists of a plate 14' of electrical insulating properties mounted in a sheet metal member comprising a base 15 and the upstanding flange or back 16. The installation illustrated being of the three-wire type, the plate is provided in its upper face with three recesses 17 in which are located the contact elements 18 each carried by a leaf spring 19 anchored to a corresponding bolt 21 which extends through the base 15 and is provided with a nut 22 by which the spring is rigidly locked in position.

The base 15 is provided with suitable openings 23 through which the bolts 21 extend so that electrical contact between the bolts and the base is prevented. These bolts also serve as binding posts for the wires 24 leading from the range bus bars, such wires being attached to the posts by the nuts 25. The panel thus wired and mounted forms a permanent mounting for the clock and presents the electrical elements 18 in position to be engaged by corresponding elements carried by the clock.

The electric clock, the mechanism of which may be of any suitable or preferred type which it is unnecessary here to illustrate, is mounted in the usual manner in a case 26, and the wires 27 extending from the clock mechanism are connected with three binding posts 28 extending through insulating blocks 29 anchored in the bottom wall of the case, the posts terminating beneath the case bottom in contact elements 31 disposed in opposed relation to the contact elements 18. When, therefore, the clock case is positioned upon the panel, as illustrated in Figs. 3 and 4, the electric circuit to the clock is closed through engagement of the various contact elements 18 and 31.

To retain the clock in assembled relation with the panel, the rear flange 16 is equipped with a tang or finger 32 adapted to be engaged in a correspondingly positioned opening 33 in the rear wall of the clock case. Forward movement of the case relatively to the panel is precluded by an upturned flange 34 on the front edge of the panel behind which the lower edge 35 of the front wall of the clock case extends as illustrated in Fig. 4.

It will be apparent, therefore, that the clock may be mounted on the panel by simply setting

it down in proper position in which it becomes detachably locked by the tang 32. When thus positioned electrical contact is established through engagement of the various contact elements 48 and 51 without the employment of exposed cords and without danger of the exertion of any strain upon the wiring within the clock case. Removal of the clock from the mounting for servicing or other purposes is readily effected by springing the upper edge of the back flange 16 rearwardly to disengage the tang 32, whereupon the clock may be lifted upwardly, as illustrated in dotted lines in Fig. 4, to free the case from the mounting and simultaneously break the electrical connections.

15 In the form of the invention disclosed in Figs. 7 to 11 inclusive, the design of the mounting is such that attachment of the clock to and detachment of the same from the mounting panel are accomplished by movement of the clock horizontally with respect to the panel instead of vertically, as in the form above described.

16 The clock in this instance is carried upon a support 36 projecting upwardly from the range 12. The support is shaped to receive and sustain 25 the weight of the clock case 37 and the mechanism therein, and carries in suitable position the mounting panel, indicated generally as 38. The panel in this instance comprises the plate 39 made of suitable insulating material and carries 30 the three contact elements 41 fixed upon the free end of the leaf springs 42 which, in turn, are anchored by the bolts 43 extending through the plate 39 and clamped thereto by the nuts 44. Each bolt serves as a binding post for the electric wires 45 which are bound in place by the nuts 46. The plate 39, in this instance, is vertically disposed instead of horizontally, as in the form first described.

17 The wires 47 within the clock, one of which is shown in Fig. 11, are each attached to a post 48 carried by an insulated block 49 mounted in the rear wall of the clock case, and the outer end of each post terminates in a contact element 51 disposed in alignment with its companion contact element 41 of the panel. Engagement of the various contact elements 41 and 51 establishes the circuit for the clock mechanism.

18 In order to hold the clock case in assembled relation with the panel, an upwardly extending 50 lip 52 of the panel frame 53 engages beneath one of the louvers 54 struck out from the back of the case. Cooperating with the lip 52 in retaining the clock and panel in assembled relation is a yielding hook-shaped lip 54' struck downwardly 55 from the bottom wall 55 of the clock case, which lip telescopes over the rearwardly projecting bottom flange 56 of the panel frame and engages in an opening or slot 57 formed therein, all as illustrated in Figs. 10 and 11.

60 To detach the clock from the panel, an upward

and outward pull is exerted upon the clock case which withdraws the louver 54 from the lip 52, whereupon the clock may be lowered to free the lip 54' from the slot 57, thereby permitting the clock to be withdrawn horizontally, as indicated in dotted lines in Fig. 11.

65 In both forms of my invention, the attachment of the clock to the panel serves to close the electric circuit, and the detachment of the clock breaks the circuit. In one instance the attachment and detachment is effected by vertical movement of the clock, and in the other instance by horizontal movement. In both instances the clock may be readily mounted and dismounted without disturbing any of the wiring either within 15 the clock case or that incorporated in the body of the range and connected with the binding posts projecting outwardly from the mounting panel.

20 While two forms of the invention have been disclosed, it is obvious that the structural details illustrated and described are capable of considerable modification and variation without departing from the essence of the invention as defined in the following claims:

I claim:

25 1. In a clock mounting, the combination of a panel adapted to be mounted upon a stove or the like and comprising a metallic frame provided at one edge with a projecting flange and having a block of insulating material mounted in the frame and provided on one face with a plurality of depressions, contact elements mounted in said depressions so as to be exposed for engagement by companion contact elements, an electric clock provided with a plurality of contact elements 30 exposed outside the case and arranged for engagement respectively with said panel contact elements, and cooperative means on the clock case and on said panel flange for detachably holding said case in predetermined position with 35 respect to said panel so as to maintain contact between the contact elements carried by the case and said panel respectively.

40 2. In a clock mounting, the combination of a panel comprising a metal base having an out- 45 standing flange and a block of insulating material secured to the base and provided on its exposed face with a plurality of depressions, contact elements mounted in said depressions, electrical connections extending from said contact elements 50 through the base of said panel, an electric clock including a case and a plurality of contact elements carried by and disposed outside of said case in position to respectively engage the contact elements of said panel, and means carried by said 55 panel flange for detachably locking said case in position on the panel so as to maintain contact between the contact elements carried respectively by the case and the panel block.

60 WILLIAM MEYNCKE. 60
